WARP KNIT FABRIC

Kurt Kaak, West Reading, Pa., assignor to The Narrow Fabric Company, West Reading, Pa., a corporation of Pennsylvania

Application October 13, 1937, Serial No. 168,713

6 Claims. (Cl. 66—192)

My invention relates to improvements in warp knit fabrics, and particularly to methods of, and means for, preventing disruption of warp knit fabrics of the elastic girdle, bandage and other types.

Amongst the difficulties experienced with fabrics of the above-indicated character, as heretofore constructed, has been the problem of preventing slippage of elastic strands, such as rubber strands, relative to fibrous yarn strands such as those of cotton, rayon or silk; this problem having been particularly difficult in warp knit fabrics of the so-called porous or open work type for use in garments of brassiere, girdle, stocking band or other bandage character.

A highly successful solution of the above-mentioned problem, heretofore suggested, is the provision of individual warp stitch yarn chains in the nature of coverings, for the respective elastic warp strands, irrespective of whether the latter have other coverings, as of wound cotton threads, previously formed thereon or not.

The warp stitch chains may be formed on the elastic warp strands to definitely prevent slippage, and the weft yarns may be so interlinked with the chains, without depending on any direct looping about the elastic warp strands, as to provide a highly desirable and successful fabric, so far as the former difficulty is concerned.

However, the above-noted solution of the aforementioned problem introduced a new problem whereby the above-mentioned warp stitch chains tend to ravel when ruptured, whereby not only to cause damage along the warps, but also to release weft yarns.

Rupture of a weft yarn without rupture of a warp stitch chain in a warp knit fabric having warp stitch chains as heretofore employed, by reason of the interlinked relation of the yarn to the warp stitch chains, although tending to more or less indefinitely and incidentally, limit disruption of the fabric by extensions of the weft yarn rupture, nevertheless is not definitely guarded against the extension of such disruption, as in the fabric of my invention, as will appear, and, of course, rupture of both a warp stitch chain and a weft yarn at the same location, or within certain linkage proximity to each other in a prior fabric, will be extended more, or cause greater disruption, than a rupture of either one alone.

Rupture of either the weft yarns or warp stitch chains may be caused by pins or other sharp objects, or by localized strain or damage of various kinds, and the chains of the fabrics as heretofore produced subjected to greater likeli-

hood of breakage and extensive disruption by reason of the outstanding positions thereof on heavy warp strands, particularly at one side of the fabric.

From such causes, a garment, as formerly made from a fabric of this type, may become not only unsightly from many small disruptions, but unwearable from one or more larger ones resulting from rupture, which readily occur, as well as to reach the end of its usefulness long before it might otherwise be considered as "worn out."

A solution of the latter problem is most highly to be desired, to which end the invention hereof is directed, with one of its objects to effect such solution in as simple a manner as possible, without adding unduly to its cost or difficulty of manufacture, and to render it a distinctly improved product.

Another object is to provide a method of producing the fabric hereof which may be practiced on a standard warp knitting machine, without any change other than variation of the pattern mechanism set up, similar to adjustments involved in any usual modification of pattern.

Another object is to definitely prevent disruption of warp knit fabrics, independently of any tendency of any part of the fabric to limit disruption incidentally.

Another object is to provide novel arrangements of yarns in fabrics of the above-indicated character for the indicated and other uses.

A further object is to obtain a fabric of definitely limited disruptive character, or of a character directly controlling parts thereof ordinarily tending to extend damage, such as distortion or destruction of the loop shapes, resulting from rupture of a yarn or yarns; this object being obtained in the example given, by the use of tie-in yarn, which may assume various novel forms, and effect various novel results, as by being laid and formed parallel to, or coincident with, other yarn, as by being smaller or stronger than the other yarn, or of different texture, and which may "bite" into the other yarn, or be caused to either add a design feature to, or be obscured by, the other yarn.

With these and other objects in view, which will become apparent from the following detailed description of the illustrative embodiment of the invention shown in the accompanying drawings, my invention resides in the novel method steps, features of construction and arrangement of parts of the fabric in cooperative relationship as hereinafter more particularly pointed out in the claims.

In the drawings:

Figure 1 is a face view, on a slightly enlarged scale, of an area of one example of elastic warp knit fabric constructed in accordance with the invention, a central portion, having a pattern like the remainder thereof, as shown, being broken away;

Fig. 2 is a detail cross sectional view, on a very greatly enlarged scale, of a portion of the central fabric area illustrated in Fig. 1, with the face, as illustrated in Fig. 1, at the top of Fig. 2;

Fig. 3 is a face view, drawn to the scale of Fig. 2, of a portion of the central area of the fabric above-mentioned, and as viewed in Fig. 1, showing ruptures of warp stitch chain and weft yarns, and how disruption is definitely limited; and

Fig. 4 is a view, drawn to the scale of Figs. 2 and 3, of a small fractional portion of the fabric thereof, showing the side or face reverse to that of Fig. 3, corresponding to the underside of Fig. 2.

Referring to the drawings, one example of a fabric constructed in accordance with the invention is substantially as shown in Fig. 1, and is of a warp knit elastic type commonly used in garments, such as girdles, brassieres, and bandages for various parts of the body, and for other use.

In this instance, the fabric comprises, in general, a main or central body area A, of repetitive pattern throughout, and disposed intermediate duplicate border areas B. The area A comprises, in general, warpwise portions 5, in relief, or forming ridges equally spaced weftwise from one another, on one face of the fabric, and weft yarn areas 6 between the ridges. The area A has one of the warpwise portions 5 at each weftwise boundary next to the corresponding border area B.

Each border B has warpwise portions 7, like the portions 5 of the area A, except as to their relation to each other; the portions 7 being disposed in pairs which are each spaced from the next adjacent pair or pairs, by weft yarn areas 8, the same weftwise distance as every other pair is so spaced from the next pair or pairs. This arrangement places a pair of the portions 7 next to a portion 5 whereby to provide triple warp strand areas C, in addition to the single and double-strand areas set forth. Each outermost pair of strands 7 appears slightly different from the other pairs by reason of the arrangement of weft threads which form more of a single cover for the two strands of the pair. Also, the borders B are not further specifically set forth herein, except that they embody the invention in a form similar to the form shown and described relative to the area A, as will be understood; the weft yarn areas 8 being of more or less closed, or less porous, character than the areas 6.

Specifically, each of the warpwise portions 5 and 7 comprises a usual warp or warp strand made up of a rubber core 10 (Fig. 2) and a covering 11 of wound cotton thread.

On each warp strand, individual thereto and independent of every other warp strand, is formed a warp stitch chain 12, as of rayon, shown in the drawings as relatively heavy, and clear white or unshaded; each chain being of such character that, if disposed alone on its warp and not linked with the weft yarn or the yarn of the invention, a rupture of a single link would cause the chain to instantly disrupt or extend the damage for a substantial distance, if not entirely, along its length. The weft yarn has some incidental indefinite deterrent effect on such disruption, but not enough to prevent the substantial

distortion and destruction of the loop shapes which the invention hereof is provided to prevent.

The main body weft yarn of the areas 6, as of rayon, is formed in recurrent cycles, each of which extends, for instance, as does one of them from a point (Fig. 3) of linkage 14 with a warp stitch chain 12 on one warp portion 5, in weftwise direction across and beyond a next adjacent warp portion 5, to a point of linkage 15 with a chain 12 on a third warp portion 5, then warpwise to a point of like linkage 16, then in reverse weftwise direction to a chain linkage point 17 on the second or intermediate warp 5, then warpwise to a point 18 on the intermediate warp, then weftwise to a point 19, and warpwise to a point 20 on the third warp, and then back across and beyond the intermediate warp 5 to a point 21 linked with the chain of the starting warp. Thus, each body weft yarn of the areas 6, has warpwise spaced long weft lengths 22, for instance, spanning two of the weft areas 6 across one of the warp portions 5, and a pair of short weft lengths 24 only bridging the space between two next adjacent warps 5; the sequence and arrangement being the same throughout, with no two of the body yarns in the area of the other, and there being alternate spaces D between the long weft lengths 22 in which no short weft lengths 24 are disposed.

The tie-in means of the invention comprises 30 a yarn 27, in this instance of silk, and of smaller diameter and greater strength than either the yarn of the warp stitch chains 12 or the yarn of the weft areas 6. There is a separate tie-in yarn 27 disposed between the warpwise portions 5 of 35 each pair thereof, each extending through recurrent cycles, for instance as does one of them from a point 30 on the first warp to the left at the upper left hand corner of Fig. 3 along a weftwise length 31 across the space between adjacent warps 40 5 to a point 32 on the second warp, then along a warp stitch chain portion 12 in the form of a warp stitch chain 33 coincident with, or along each loop of, the chain 12 to a point 34 and back, along a weftwise length 35 to a point 36 on the 45 original warp 5.

The tie-in yarns 27, by reason of the smaller diameter thereof, may be caused to "bite into" the larger yarns of the warp stitch chains 12 and the weft areas 6, whereby with their multi-point 50 linkage with these yarns, and the cyclic configurations different from the configuration of the body yarn, to form a definite disruption stopping point at each linkage; examples of the result of rupture of a warp stitch chain 12 being indicated 55 in Fig. 3 at a position E, and of a weft yarn at a position F. In each instance the broken yarn is tied or gripped at each side of the rupture by the tie-yarn 27 at a loop or bight of one of the 60 cover chains.

The side of the fabric shown in Fig. 4 is of flatter form, and simpler loop configuration, as contrasted with the opposite face of the fabric in Fig. 3 on which the warpwise portions 5 upstand, with the consequent more extensive showing of 65 the warp stitch chains and other portions.

In the arrangement whereby the weft yarns of the areas 6 extend back and forth between the chains 12 in warpwise spaced groups 38 (Fig. 1), the spaces D are thereby formed between these 70 groups to give the fabric its porous character, which may be varied by a selection of patterns.

Of course the improvements specifically shown and described by which I obtain the above results, can be changed and modified in various 75

ways without departing from the invention as herein disclosed and hereinafter claimed.

I claim:

1. A warp knit fabric including warps, yarns having warp stitch chain portions covering said warps, yarns having weft portions and warp stitch chain portions following the warp stitch chain portions of said first yarns, and strands having warp and weft portions and linking the chains of said yarns.
2. A warp knit fabric including warps, yarns having warp stitch chain portions covering said warps, yarns having weft portions and warp stitch chain portions coincident with the warp stitch chain portions of said first yarns, and strands having warp and weft portions and linking the chains of said yarns.
3. In a complete standard warp knit fabric structure comprising parallel elastic body warps, interlooped cover yarns for the body warps subject to runs, and threads holding the cover yarn of the respective warps to each other; a run guard strand interlaced between the cover yarns and holding threads in such manner that bights of the run guard strand are uniformly interspersed in locking relation with the cover yarns and holding threads of the fabric structure, whereby the latter is protected against disruption as a result of rupture of the yarns or threads at any particular point.
4. In a complete standard warp knit fabric structure comprising parallel elastic body warps, interlooped cover yarns for the body warps subject to runs, and threads holding the cover yarn of the respective warps to each other; a run guard strand of smaller diameter than said warps and threads interlaced between the cover

yarns and holding threads in such manner that bights of the run guard strand are uniformly interspersed in locking relation with the cover yarns and holding threads of the fabric structure, whereby the latter is protected against disruption as a result of rupture of the yarns or threads at any particular point.

5. In a complete standard warp knit fabric structure comprising parallel elastic body warps, interlooped cover yarns for the body warps subject to runs, and threads holding the cover yarn of the respective warps to each other; a run guard strand of greater tensile strength than said warps and threads interlaced between the cover yarns and holding threads in such manner that bights of the run guard strand are uniformly interspersed in locking relation with the cover yarns and holding threads of the fabric structure, whereby the latter is protected against disruption as a result of rupture of the yarns or threads at any particular point.

6. In a complete standard warp knit fabric structure comprising parallel elastic body warps, interlooped cover yarns for the body warps subject to runs, and threads holding the cover yarn of the respective warps to each other; a run guard strand of smaller diameter and greater tensile strength than said warps and threads interlaced between the cover yarns and holding threads in such manner that bights of the run guard strand are uniformly interspersed in locking relation with the cover yarns and holding threads of the fabric structure, whereby the latter is protected against disruption as a result of rupture of the yarns or threads at any particular point.

KURT KAAK.
